AIRPLANE TOY

Tiberiu J. Rammiceanu, 3457 Cottman Ave.,
Philadelphia 49, Pa.

Filed July 15, 1959, Ser. No. 56,790

Term of patent 14 years

(Cl. D34—15)

Fig. 1 is a perspective view of an airplane toy showing my new design as it appears in use;

Fig. 2 is a front view of the toy shown in Fig. 1;

Fig. 3 is a rear view;

Fig. 4 is a top plan view; and

Fig. 5 is a bottom plan view.

The portion shown in broken lines is for illustrative purposes only.

I claim:

The ornamental design for an airplane toy, as shown and described.
